UNITED STATES PATENT OFFICE.

FREDERICK SMITH, OF WORCESTER, MASSACHUSETTS, ASSIGNOR TO HARRINGTON & RICHARDSON ARMS COMPANY, A CORPORATION OF MASSACHUSETTS.

TRIGGER-LOCKING DEVICE.

1,119,124.

Specification of Letters Patent.

Patented Dec. 1, 1914.

Application filed November 21, 1913. Serial No. 802,186.

To all whom it may concern:

Be it known that I, FREDERICK SMITH, a citizen of the United States, residing at Worcester, in the county of Worcester and 5 State of Massachusetts, have invented a new and useful Trigger-Locking Device, of which the following is a specification.

The object of this invention is to improve magazine fire-arms, particularly that class 10 of fire-arms in which the cartridges are placed in a magazine, which magazine is inserted in the frame of the fire-arm so that the cartridges will be fed automatically.

The specific type of fire-arm to which the 15 invention is more particularly adapted is that type of magazine fire-arm in which the recoil ejects the shell, brings a new cartridge into position, and cocks the fire-arm.

In fire-arms of the class above mentioned, 20 and particularly of the type referred to, the magazine is often withdrawn for loading or for other purposes before all the cartridges have been fired, so that an unfired cartridge will be left in the fire-arm.

25 Sometimes when the magazine is withdrawn under these conditions, the trigger is snapped or the fire-arm is tried by the person handling the same, as he is led to believe, by the removal of the magazine, that 30 the fire-arm has been rendered inoperative. Under these conditions, accidents are apt to occur.

The object of this invention is to do away with this danger.

35 The invention consists in providing a locking mechanism controlled by the magazine and connected so that the fire-arm will be operable only when the magazine is in the frame. The locking mechanism is preferably arranged to coöperate with the trigger and consists specifically of a spring-pressed trigger engaging catch and an operating hook therefor pivoted in the frame and having a shoulder adapted to engage 40 the frame to limit the movement of the catch and set in position to be engaged by the magazine so that the trigger will be operable only when the magazine is in the frame.

45 One form of the invention is illustrated in the accompanying drawings, referring to which,

Figure 1 is a side elevation partly in section of a fire-arm with my improvement applied thereto; Fig. 2 is an enlarged sectional

elevation illustrating the locking mechanism in the position which it assumes when the magazine is in the fire-arm; and Fig. 3 is a similar view illustrating the position of the locking mechanism when the magazine 60 is removed.

In detail, A designates the fire-arm and B designates the magazine or cartridge holder which can be inserted in the frame of the fire-arm.

C designates the trigger which has an extending projection or point C'. The trigger is connected by any of the usual links or other means to the sear or the firing mechanism.

A catch made in the form of a plunger pin D is inserted in a hole bored in the frame, a spring E being placed under the catch to force the same normally upward. An operating hook F is pivoted in the frame 75 just back of the catch D and has its head or jaw extending over the top of the catch. The hook F is provided with a shoulder F' adapted to engage the frame to limit its movement to the right, as shown in the 80 drawings, whereby the upward movement of the catch D is limited. When the catch D is in its uppermost position, the same comes in the path of the trigger C, as shown in Fig. 3. When the parts are in this 85 position the hook F comes in the path of the magazine. When the magazine is inserted in the fire-arm, it engages the hook F and throws the head of the hook to the left, as shown in Fig. 2, so that the catch 90 D will be depressed. When the catch is in depressed position, it is moved out of the path of the trigger. By this arrangement, the fire-arm will be operable only when the magazine is in the frame, and when the 95 magazine is withdrawn from the frame, it will be impossible to pull the trigger to operate the firing mechanism.

The improved mechanism may be applied in other ways to the fire-arm, and the details and arrangements herein shown and described may be greatly varied by a skilled mechanic without departing from the scope of the invention as expressed in the claim.

Having thus fully described my invention, what I desire to secure by Letters Patent is,—

In a magazine fire arm, in combination, a frame having a recess therein, a trigger, a cartridge magazine removably fitted in

the frame, and a locking device for said trigger comprising a plunger longitudinally movable in said recess, a spring to move the plunger into the path of trigger to lock it in inoperative position, and a releasing lever pivoted to the frame and having a hook shaped projection at one end overlying the end of the plunger, said lever

tive to force the plunger into the recess 10 thereby releasing the trigger.

In testimony whereof I have hereunto set my hand, in the presence of two subscribing witnesses.

FREDERICK SMITH.
